UNITED STATES PATENT OFFICE.

SAMUEL D. WEBB, OF WASHINGTON, DISTRICT OF COLUMBIA.

DESIGN FOR A SASH-HOLDER.

SPECIFICATION forming part of Design No. 32,622, dated May 1, 1900.

Application filed March 31, 1900. Serial No. 11,023. Term of patent 14 years.

To all whom it may concern:

Be it known that I, SAMUEL D. WEBB, a citizen of the United States, residing at Washington, in the District of Columbia, have invented and produced a new and original Design for Sash-Holders; and I do hereby declare the following to be a full, clear, and exact description of the same, reference being had to the accompanying drawings, forming a part thereof.

Figure 1 is a plan view of a sash-holder, showing my new design, while Fig. 2 is a sectional view taken on the line $x-x$ of Fig. 1.

As shown in the said drawings, the leading or material feature of my design consists of a pear-shaped disk having a centrally-raised portion A, representing the Washington Monument, with wedge-shaped or tapering portions B on each side thereof, said taper-

ing sides having a series of grooves or corrugations C, while at the upper or narrow portion of the pear-shaped disk is a small circular opening D, as fully shown in Fig. 1. The central raised portion A, representing a tall shaft or monument, is left plain, while the tapering sides are corrugated, as shown.

Having described my invention, what I claim as new, and desire to secure by Letters Patent, is—

The design for a sash-holder, as herein shown and described.

In testimony whereof I affix my signature in presence of two witnesses.

SAMUEL D. WEBB.
